UNITED STATES PATENT OFFICE.

AARON STERN AND JOHN McLEAN, OF NEW YORK, N. Y.; SAID McLEAN
ASSIGNOR TO SAID STERN.

ICE-CREAM FREEZER.

SPECIFICATION forming part of Letters Patent No. 758,791, dated May 3, 1904.

Application filed May 8, 1903. Serial No. 156,293. (No model.)

To all whom it may concern:

Be it known that we, AARON STERN and JOHN McLEAN, citizens of the United States, residing in the borough of Manhattan, city of New York, in the county of New York and State of New York, have invented certain new and useful Improvements in Ice-Cream Freezers, of which the following is a specification, reference being had therein to the accompanying drawings.

This invention relates to freezers for ice-cream, ices, sherbets, &c., and has for its objects simplicity of construction, adaptability to the freezing of a number of varieties of ice-cream, ices, or sherbets at the same time or of a less number than the maximum capacity of an apparatus, ease and effectiveness of operation, and ready separation and assembling of parts.

According to this invention a plurality of containers is provided, and these containers are rotatably mounted and connected so as to rotate together, and according to our invention the containers are independently rotatably mounted, and means are provided for applying rotative movement to one of the containers, and thereby rotating all of them.

The invention also includes the provision of an exterior casing for all of the containers and of removable separating partitions, providing compartments for the several containers, so that the use of the containers may be limited to any number less than the whole number of containers provided in the apparatus, and by the partitions the space for freezing medium may also be limited to the space immediately about the container or containers in use.

The invention also includes the provision of readily-separable parts composing the freezer, so that the containers, or one or more of them, may be readily removed and inserted and the parts thereof separated for cleaning, and includes various improvements in the construction and combination of parts.

We will now describe the construction of freezer shown in the accompanying drawings and embodying our invention and will thereafter point out our invention in claims.

Figure 1 is a longitudinal sectional elevation

of the freezer. Fig. 2 is a plan view of the same with the cover of the exterior casing or box open. Fig. 3 is a central transverse vertical section of the upper part of the freezer. Fig. 4 is a section of the same on the line 4-4 of Fig. 3.

55

The several parts of the freezer are inclosed within an exterior casing or box *a*, having a hinged lid or cover *b*.

The freezer shown is adapted for freezing at the same time as many as three varieties of ice-cream, ices, or sherbets, and three separate containers 1, 2, and 3 are provided, and the box is provided with removable partitions 6 and 7, sliding in guides or grooves 4 and 5, respectively, on the inside faces of the box 65 and arranged between the containers, so as to provide a separate compartment for each container. When all of the containers are in use, the partitions may be removed and the whole of the space about the several containers supplied with the freezing medium, and any one or two of the containers when not in use may be separated by a partition or partitions and only the space about the container or containers in use may be supplied with the freezing medium, thus adapting the apparatus to the economical use of only one of the containers or of as many of the containers as desired.

75

Each of the containers has a conical projection at its bottom having a bearing in a step 8 at the bottom of the box and is provided with a removable cover 9, having a bearing on a centrally-arranged bar 10, this bar 10 being held from rotation by an upper squared part entering a square socket in a removable longitudinal upper bar 11 and extending down to the bottom of the container and having a conical lower end entering a counterpart depression in the bottom of the container. Each cover 9 has a central boss bearing upwardly 90 against the bottom of the longitudinal upper bar 11. Thus each container is freely rotatable about its central bar 10. Each central bar 10 is provided with inclined agitating-vanes 12 and also with cross-bars 13, carrying 95 the scrapers 14.

Each of the covers 9 fits tightly upon and over its container and engages therewith, so

as to impart its rotative movement thereto, as by a pin 15 on the cover engaging with a projection or lug 16 on the container. The agitating-vanes 12 are inclined so as to force the cream or other material downward, and thereby very effectively agitate the same. Each of the covers 9 is also provided with a spur-gear 17, formed on its rim and meshing with the corresponding gear on the cover of the 10 adjacent container, so that motion transmitted to one container will be imparted to the other containers, the adjacent containers rotating in opposite directions.

For the purpose of imparting rotation to the 15 containers I provide a bevel-gear 18, formed upon the cover of the central container 2 and meshing with a pinion 19 on a short driving-shaft 20, which is fitted to rotate in a hinged bracket 21 and is squared at its outer end to 20 receive an operating wheel or crank and handle. The bracket 21 is hinged at the back of the box 1, and, as shown, a spring 22 is provided at the hinge 29 to take up any looseness of parts and prevent rattling and also to initially lift the bracket, and hinged catches 23 are provided at the front of the box, engaging projections at the edges of the bracket 21 and yieldingly held in engagement therewith by a spring 24. The front end of the bracket 25 21 passes through the front of the cover of the box, and its front face is flush therewith, so that the only protruding part is the squared front end of the driving-shaft 20. Hooks 25 are provided for holding the cover 2 of the 30 box in closed position. These hooks may be disengaged and the cover swung up and back on its hinges, and thereafter the catches 23 may be disengaged and the bracket 21 also swung up and back on its hinges. The longitudinal upper bar 11 will then have all parts 35 above it removed, and this longitudinal bar is detachably held, so that it may be readily removed, being removably seated at one end in a grooved socket-piece 27 and having a spring-bolt 28 at the other end thereof. After the longitudinal bar 11 has been removed the several containers may be readily lifted out, their covers removed, and they may be filled with the material to be frozen, or the 40 frozen material may be removed from them, the central bars 10 and agitators and scrapers thereon being readily removable from the containers.

If it is desired to use only one retainer at a 45 time, the retainers 1 and 3 need not be inserted in the freezer, the partitions 6 and 7 being retained in place and only the space about the container 2 and between the two partitions supplied with the freezing medium.

So, also, only the containers 1 and 2 or 2 and 60 3 may be used and in place, with the partition between the two containers in use removed and the other partition in place to confine the freezing medium to the space about the containers in use, as above described. 65

The ready detachability of all parts of the freezer also permits separate and complete cleaning of all parts and sterilization of all parts which come in contact with the material to be frozen. 70

The longitudinal upper bar 11 is provided on its lower face with annular grooves 26 about the bearings of the covers, so that fluid which falls upon the bar cannot enter the bearings or enter the containers. 75

It is obvious that the number of containers provided in an apparatus embodying the invention may be greater or less than in the construction shown and that various modifications may be made in the construction shown 80 and above particularly described within the spirit and scope of the invention.

What we claim, and desire to secure by Letters Patent, is—

1. In a freezer, the combination of a plurality of rotatable containers, an exterior casting having bearings for the lower ends of the containers, a movable upper bar, agitators located within the several containers and seated in the upper bar so as to be held from rotation, each of the containers including a cover having a bearing upon the agitating means and the several covers being connected one to another so as to transmit motion from one to another, and means for applying rotative movement to one of the covers. 85

2. In a freezer, the combination of a plurality of rotatable containers, an exterior casting having bearings for the lower ends of the containers and movable partitions between the containers, a movable upper bar, stationary agitators located within the several containers and seated in the upper bar, each of the containers including a cover having a bearing upon the agitating means and the several 90 covers being connected one to another so as to transmit motion from one to another, a hinged bracket carrying a driving-shaft, and motion-transmitting means connecting the driving-shaft to one of the containers, substantially as set forth. 100

In testimony whereof we have affixed our signatures in presence of two witnesses.

AARON STERN.
JOHN McLEAN.
